(57) **CLAIM**

The ornamental design for an electrosurgical return electrode with patient map, as shown and described.

DESCRIPTION

FIG. 1 is a perspective view of an electrosurgical return electrode with patient map showing the new design;

FIG. 2 front view thereof;

FIG. 3 is a first side view thereof;

FIG. 4 is a second side view thereof;

FIG. 5 is a third side view thereof;

FIG. 6 is a fourth side view thereof; and,

FIG. 7 is a back view thereof.

The broken lines are for illustrative purposes only and form no part of the claimed design.

1 Claim, 3 Drawing Sheets

FIG. 1

FIG. 7
